US00D988984S

(12) **United States Design Patent** (10) Patent No.: **US D988,984 S**
(45) Date of Patent: **** Jun. 13, 2023**

(54) **BATTERY PACK**

- (71) Applicant: **Walmart Apollo, LLC**, Bentonville, AR (US)
- (72) Inventors: **Darius Z. Osmola**, Rogers, AR (US); **Tabatha M. Hunter**, Centerton, AR (US); **XiaoFei Yang**, Guangzhou (CN)
- (73) Assignee: **Walmart Apollo, LLC**, Bentonville, AR (US)
- (**) Term: **15 Years**
- (21) Appl. No.: **29/763,111**
- (22) Filed: **Dec. 21, 2020**

Related U.S. Application Data

- (62) Division of application No. 29/627,988, filed on Nov. 30, 2017, now Pat. No. Des. 958,061.

(57) **CLAIM**

The ornamental design for a battery pack, as shown and described.

DESCRIPTION

FIG. 1 is a top front perspective view of the battery pack according to our new design;

FIG. 2 is a top plan view thereof;

FIG. 3 is a left side elevation view thereof;

FIG. 4 is a right side elevation view thereof;

FIG. 5 is a bottom plan view thereof;

FIG. 6 is a rear elevation view thereof;

FIG. 7 is a front elevation view thereof; and,

FIG. 8 is a top rear perspective view thereof.

The broken lines depict portions of the battery pack that form no part of the claimed design.

1 Claim, 4 Drawing Sheets
